UNITED STATES PATENT OFFICE.

WILLIAM A. RINGLER, OF PHILADELPHIA, PENNSYLVANIA, ASSIGNOR TO GLOBE-WERNICKE CO., OF CINCINNATI, OHIO, A CORPORATION OF OHIO.

DISPLAY DEVICE.

Application filed April 4, 1922. Serial No. 549,446.

To all whom it may concern:

Be it known that I, WILLIAM A. RINGLER, a citizen of the United States, residing at Philadelphia, county of Philadelphia, State 5 of Pennsylvania, have invented a new and useful Display Device, of which the following is a specification.

My present invention comprehends a novel construction and arrangement of a display 10 device formed from one or more metallic strips which are lapped upon themselves in such a manner as to form a series of resilient pockets which will yieldingly hold in place any desired material which it is desired to 15 display, such as for example, stencils, cards, many different types of notices and memoranda, small tools and in fact any desired type of article.

It further comprehends a novel construction 20 of a display device of the character aforesaid and novel means for securing it in position with respect to a support.

Other novel features of construction and 25 advantage will hereinafter more clearly appear in the detailed description and the appended claims.

For the purpose of illustrating my invention, I have shown in the accompanying drawings embodiments thereof which are at 30 present preferred by me, since these embodiments will be found in practice to give satisfactory and reliable results. It is, however, to be understood that the various instrumentalities of which my invention consists can be variously arranged and organized 35 and that my invention is not limited to the precise arrangement and organization of these instrumentalities as herein shown and described.

40 Figure 1 represents, in side elevation, a display device, embodying my invention.

Figure 2 represents, in front elevation, the construction seen in Figure 1, in assembled position with respect to a support.

45 Figure 3 represents, in side elevation, the construction seen in Figure 2.

Figure 4 represents, in front elevation, a plurality of strips and their supports.

50 Figure 5 represents a section on line 5—5 of Figure 4.

Figure 6 represents a front elevation of a support and certain of its adjuncts.

Figure 7 represents, in side elevation, a plurality of aligned display strips showing more particularly the manner in which two 55 strips can be connected together.

Similar numerals of reference indicate corresponding parts.

Referring to the drawings.

The display device in its simplest form 60 consists of a strip of material 1 preferably made of metal which is folded upon itself to form the pockets 2, the strip being provided with the upwardly extending portions 3 which merge into the downwardly extending portions 4 at the back by means of the curved hinge forming portion 6. The portion 3 terminates above the curved hinge forming portion 5 of a superimposed pocket and is rounded, as at 6, and then extends 65 70 downwardly, as at 7, a sufficient distance to form the desired depth of the pocket 2. The free ends 8 of the strip form terminals so that such free ends can be secured to a support 9, which forms a backing, by means of 75 fastening devices 10. The strip is stiffened intermediate its ends by means of the fastening devices 11 which consist of straight pieces of wire, as shown, having the free 80 ends deflected to form the eyes 12 through 13 which are passed fastening devices 13.

In Figures 4 and 5, I have shown a plurality of the strips 1 secured to a support 9 with a modified form of fastening device to contribute to support the strips at spaced 85 intervals throughout their length. In this embodiment of fastening device, 14 designates the fastening device which consists of a strip of material such as sheet metal secured to the support at desired intervals 90 by means of fastening devices 15 and having its free end off set, as indicated at 16. The off-set portion 16 is adapted to have a strip slid over it so that it is positioned between the downward extension 7 and the 95 upward extension 3, as will be understood by reference to Figure 5.

It will be apparent from Figure 7 that different strips can be readily connected together by simply interlocking the terminal 100 loop at the end of one strip with the terminal loop of an aligned strip and then locking the strips together by effecting relative lateral or longitudinal movement of

such strips. The terminal portion of one strip is shown in Figure 7 at 17 and the terminal portion of the other strip is indicated by 18.

5 19 designates an article which is to be displayed. It will be seen that when an article is inserted in position in a pocket the construction is such that a resilient locking action takes place, the grip being effected intermediate the top and bottom of the pocket. It will be understood that when the top of a pocket is bent outwardly such movement is resisted by the top portion of the next pocket so that a resilient locking 10 action takes place.

15 It will be apparent that my present invention in its simplest form consists simply of a single display strip as herein disclosed which can be secured to any desired article 20 or object or one or more of them can be secured to a support.

25 It will now be apparent that I have devised a new and useful display device which embodies the features of advantage enumerated as desirable in the statement of the invention and the above description, and while I have, in the present instance, shown and described preferred embodiments thereof which will give in practice satisfactory 30 and reliable results, it is to be understood that such embodiments are susceptible of modification in various particulars without departing from the spirit or scope of the invention or sacrificing any of its advantages.

35 Having thus described my invention,

what I claim as new and desire to secure by Letters Patent, is:—

1. A display device, comprising a strip of sheet material overlapped upon itself to 40 form a series of pockets extending in the same direction with double outer walls, the inner walls of one pocket acting resiliently on the outer walls of an adjacent pocket only at points intermediately of the top 45 and bottom of such adjacent pocket.

2. A display device, comprising a strip of sheet material overlapped upon itself to 50 form a series of pockets extending in the same direction and having its free ends forming terminals, a support, and means seated in certain of said pockets to secure said strip to said support.

3. A display device, comprising a strip of sheet metal overlapped upon itself to 55 form pockets having a single inner wall and a double outer wall, the double outer wall of one pocket resiliently engaging the double outer wall of an adjacent pocket.

4. A display device, comprising a plurality of strips of sheet metal spaced from 60 each other, each strip being overlapped upon itself to form a series of pockets with a single inner wall and an outer double wall which latter resiliently bears against the 65 double outer wall of the superimposed pocket.

WILLIAM A. RINGLER.
